(57) **CLAIM**

The ornamental design for a strap length adjuster, as shown and described.

DESCRIPTION

1. Strap length adjuster

1.1 : Perspective

1.2 : Front

1.3 : Back

1.4 : Top

1.5 : Bottom

1.6 : Left

1.7 : Cross sectional

The letters ('A') and the arrows in reproduction 1.4 are only to show a part of cross section and form no part of the claimed design.

The portions of the strap length adjuster shown in broken lines here form no part of the claimed design.
